UNITED STATES PATENT OFFICE.

HENRY C. HART, OF DETROIT, MICHIGAN, ASSIGNOR TO THE VAN WAGONER
& WILLIAMS COMPANY, OF NEW YORK.

SPRING-HINGE.

SPECIFICATION forming part of Letters Patent No. 431,349, dated July 1, 1890.

Application filed January 31, 1889. Serial No. 298,299. (Model.)

To all whom it may concern:

Be it known that I, HENRY C. HART, of Detroit, in the county of Wayne and State of Michigan, have invented a new and useful Improvement in Double-Acting Spring-Hinges, of which the following is a specification.

My invention consists in an improvement in double-acting spring-hinges, hereinafter fully described and claimed.

10 Figure 1 is a front elevation. Fig. 2 is a side elevation; Fig. 3, a cross-section on line xx , Fig. 1; Fig. 4, a perspective of the spring, and Fig. 5 a perspective of a hook forming the end of the spring, by which it connects 15 with the leaf.

G and F represent the two leaves of a double-acting spring-hinge, the pintle-line being thrown forward from the plane of the leaves, as is usual in this form of hinge.

20 E represents a bow-spring of steel, whose ends are pivotally connected with the leaves G F at a point between said leaves and the pintle-line, as shown in Fig. 3, whereby the action of the spring E will hold the hinge 25 closed, or, after opening a certain distance, will hold the hinge open, as shown in dotted lines, Fig. 3.

The ends of the spring E may be formed into hooks to engage directly with the leaves; but it is usually easier to make 30 the hook of some softer metal than the spring and connect the ends of the spring therewith. Such a hook is represented in Fig. 5, in which a bar A has formed at its two ends the hooks C and carries three projecting lugs, the

35 end ones B B being on the same side and the center one D being on the other side, so that the end of spring E will lie between the lugs D B B and be held therein by the pressure of the spring. The hooks C C en- 40 gage with pins H H, formed on the leaves G F.

The operation of this hinge is as follows,

reference being had particularly to Fig. 3: When the hinge is closed—that is, in the position shown in full lines in Fig. 3—the force of the spring E, acting on pins H, tends to draw 45 said pins together, and, as they are located between the plane of the leaves and the pintle-line, holds the hinge closed. When the hinge is opened, one of the pins H travels in a circle whose center is the pintle of the 50 hinge, and the distance between the pins H on the opposite leaves constantly increases until a straight line between said pins H cuts the pintle-line of the hinge. This is called the “dead-point” of the hinge, and at this 55 point the spring E has no effective action. If the opening of the hinge be continued, as soon as the line between the two pins H passes the pintle-line the force of the spring E draws the pins H toward each other and holds the 60 hinge open, as shown in dotted lines in Fig. 3. It is evident that this construction permits the use of a continuous pintle instead of two short pintles.

What I claim as my invention, and desire 65 to secure by Letters Patent, is—

1. In a double-acting spring-hinge, the combination of two leaves having their pintle-line outside of the plane of said leaves, and a bow-spring having its opposite ends pivotally 70 connected, respectively, with said leaves between the plane of the leaves and the pintle-line, substantially as shown and described.

2. A hinge consisting of leaves F and G, a bar A, having projecting lugs B B D and 75 hooks C, connected with parts of a hinge-leaf, and a bow-spring E, held by said lugs, substantially as described.

HENRY C. HART.
